PUMP

Sherwood C. Bliss, Buffalo, N. Y., assignor to
 Houde Engineering Corporation, Buffalo, N. Y.,
 a corporation of New York

Application July 1, 1939, Serial No. 282,447

1 Claim. (Cl. 220—46)

This invention relates to pumps and more particularly to pumps of the rotary type for delivering fluid, such as oil, under pressure to hydraulically operated devices.

An important object of the invention is to produce a pump in which rotors of generally elliptical cross-section rotate in cylinders of circular cross-section, with the spaces between the rotors and cylinder walls forming working chambers alternately connectable with fluid inlet and discharge ports, together with radially urged blades engaging with the outer peripheries of the rotors to cooperate with the working spaces for alternate fluid intake and fluid discharge.

A further important object is to set the rotors for angular spacing of the working chambers and to locate the inlet and discharge ports so that there will be balanced operation for constant flow and elimination of pulsation.

A further object is to provide improved means for sealing the pump structure against the entrance of air, and to prevent the trapping or local accumulation of fluid particularly in the blade chambers so that the blades may at all times freely function for cooperation with the rotor elements.

Another important object is to provide improved sealing means for preventing the leakage of fluid from the pump structure.

Still another object is to materially reduce the number of parts for the pump and to make a number of the parts interchangeable so as to facilitate assembly of the pump.

The above enumerated and other important features of the invention are incorporated in the structure shown on the drawings, on which drawings:

Figure 1 is a plan view of the pump;

Figure 2 is an enlarged end view of the pump with the outer closure wall and outer plate removed and with the blade structure in section;

Figure 3 is a section on plane III—III, Figure 2;

Figure 4 is a section on plane IV—IV, Figure 3; and

Figures 5 and 5A diagrammatically show more clearly the cooperation of the rotors and blades for intake and discharge.

The pump housing comprises the cylindrical wall 10 having the inner head 11 integral therewith and having an outer closure and clamping head 12 insertable into the open end of the wall 10. A drive shaft 13 extends through the passageway 14 of the head 11 and has the reduced outer end 15 which receives the inner ring of a ball bearing assembly 16 whose outer ring is

seated within the recess 17 provided in the outer wall 12. The reduced inner end 18 of the shaft receives the inner ring of a ball bearing assembly 19 whose outer ring is seated in the recess 20 provided in the head 11. A cover or retainer member 21 is secured to the outer end of the head 11 as by screws 22 and has the passageway 23 for the end 18 of the shaft 13, the projecting end of the shaft being adapted to mount a driving source such as an electric motor (not shown). The member 21 may also serve as a bracket by means of which the pump structure may be supported.

The outer ring of the ball bearing assembly 19 is backed by a washer 23 in the recess 20, and a recess 24 in the closure member 21 receives a washer 25, a steel washer 26 being interposed between the member 21 and the end of the head 11 and between the washer 25 and the outer ring of the bearing assembly 19. Behind the washer 23 the head has a recess 27 for packing material 28 around the body of the shaft 13, and the member 21 has the recess 28 behind the washer 25 for packing material 28' for surrounding the end 18 of the shaft, this packing material effecting a seal against escape of fluid from the interior of the pump housing.

The pump cylinder forming elements are rings and plates clamped together between the inner face of the head 11 and the clamping wall 12. As shown there are two rings 29 and 30 respectively, an inner plate 31, an intermediate plate 32, and an outer plate 33, the outer diameters of the rings and plates being such that the rings and plates will fit snugly in the cylindrical bore of the wall 10. An annular clamping ring 34 has thread engagement in the outer end of the wall 10 and by the pressure exerted by this clamping ring, the pump rings and plates will be securely clamped between the inner face of the head 11 and the outer wall 12. To facilitate alignment of the rings and plates, they may be provided with holes 35 for dowel pins 36 which at their inner end may be anchored in the head 11, these dowel pins also preventing rotational displacement of the pump rings and plates.

The rings 29 and 30 and the plates 31, 32, and 33 define annular cylinder spaces 37 and 38 into which the rotor members 39 and 40 respectively extend to be rotated by the drive shaft 13, the shaft having splines or keys 41 engaging in the keyways 42 in the rotors. As shown on Figure 3, the radial depth of the annular plates 31, 32 and 33 is such that they will leave sufficient clearance for operation of the shaft and the rotors.

Referring to Figure 2, the rotor elements 39

and 40 are of generally elliptical shape. Primarily they may be cylindrical and then opposite sides cut away to a lesser diameter so that when the rotors are in their respective cylinder spaces 31 and 38 working chambers will be formed between the rotors and the rings 29 and 30. Where two rotors are used as shown, they will be displaced 90° on the shaft 13 so that the opposite working chambers 43 and 44 between the rotor 39 and the ring 29 will be displaced respectively 90° from the working chambers 45 and 46 between the rotor 40 and the ring 30.

The housing head 11 is cored out to provide a suction or intake space S, and a discharge space D, the suction space or chamber S having the inlet 47 connected by suitable piping with a source of fluid such as oil, and the discharge space or chamber D having the outlet 48 connectable by suitable piping with hydraulic devices for receiving the fluid under pressure.

For the cylinder spaces 31 and 38 in which the rotors 39 and 40 operate, fluid inlet and outlet ports are provided. As shown on Figure 2, each cylinder space has diametrically opposite inlet ports 49 and 49' and diametrically opposite discharge ports 50 and 50'.

Referring to Figure 3, the rings 29 and 30 have transverse bores 51 therethrough for alignment with the transverse bores 52 in the plates 31, 32 and 33 to form an intake passageway which registers with the inlet opening 53 in the head 11 communicating with the intake or suction chamber S. The ports 49 extend radially from the bores 51 through the rings 29 and 30 to communicate with the cylinder spaces 31 and 38 so that the suction chamber S in the head is in communication with the cylinder spaces for a supply of fluid thereto. Referring to Figure 2, the ring 29 has the cross wall or passageway 54 therethrough and the other ring 30 and the plates 31, 32 and 33 have passageways therethrough registering with the passageway 54, to provide a discharge path connected with the cylinder spaces 31 to 38 by way of the port 50, and the passageway registering with the discharge opening 55 in the head 11 which communicates with the discharge chamber or space D in the head. In like manner, the rings and plates are provided with registering cross bores to provide a passageway 56 between the ports 49' and the opening 57 communicating with the inlet or suction chamber S in the head 11. In the same manner a discharge passageway 58 is provided through the rings and walls for registering with the opening 59 communicating with the discharge chamber D in the head 11. The ports 49' connect the passageway 56 with the cylinder spaces 31 and 38 and the ports 50' connect the discharge passageway 58 with the cylinder spaces as clearly shown on Figure 2.

Describing now the blade structure and operation, the rings 29 and 30 are each provided with diametrically opposite blades 60 and 61 for cooperating with the rotors surrounded by the respective rings. The blades operate in radially extending slots 62 cut into the rings from the inner surfaces thereof; each blade having a socket receiving the lower end of a stem 64 which extends radially outwardly and is guided in a passageway 64' in the ring, the outer end of the pin projecting into a plug 65 seated in a threaded opening 66 in the cylindrical wall 10 of the pump housing. Each stem has a collar 67 between which and the head of the plug 65 is interposed a compression spring 68 so that the blade is yield-

ably shifted downwardly by the stem for engagement at its inner end with the surface of the respective rotor, the end of the blade being biased off as clearly shown on Figure 2 so as to have only edge engagement with the rotor. Referring to Figures 2 and 3, the upper blades 61 are midway between the inlet and discharge passageways 56 and 58, while the lower blades 60 are midway between the inlet and discharge passageways 51 and 54, the blades being thus between the respective ports leading from the passageways to the cylinder faces of the rings. The rotor engaging edges of the blades are directed toward the respective discharge passageways, the rotors rotating in the direction of the arrow on Figure 2.

Referring to the diagrammatic layout of Figure 5, the two rotors 39 and 40 are shown moving together in direction of the arrows relative to the rings 29 and 30, 61 representing the upper blades 15 located between the inlet and discharge passageways 56 and 58 respectively from which the ports 49 and 50 lead for cooperation with the working chambers 43, 44 and 45 and 46 under control of the blades. The blade for the rotor 39 is shown in engagement with the cylindrical portion 20 of the rotor while the blade for the rotor 40 is in engagement with a cut away portion of the rotor which forms the working chamber. Starting with the position shown in Figure 5, rotation of the 25 rotors will carry the hydraulic chamber 46 past the blade 61 which extends therewith and the fluid will be forced out of this chamber into the port 50' and through passageway 58 into the discharge chamber D of the pump head 11. While the chamber 46 at one side of the blade is discharging, the portion of the chamber at the opposite side of the blade is increasing in size and therefore draws in fluid from the intake space S of the pump head and through the port 49'.

While the rotor 40 is thus discharging, a cylindrical portion of the rotor 39 is traveling past its blade 61, the working chamber 43, at the position shown in Figure 5, having just completed a fluid intake operation through the intake port 49'. As soon as the working chamber 44 of the rotor 39 reaches the blade 61, this chamber will be discharged through the outlet port 50', the discharge of this chamber being displaced 90° from the discharge operation at the chamber 46 in the rotor 40. At 180° of travel of the rotors, the working chamber 46 of the rotor 40 will receive the blade 60 (Figure 2) and the chamber will be discharged through the discharge port 50, and when the working chamber 44 reaches its blade 60 it will be discharged 90° behind the discharge of the chamber 46 in rotor 40. The four working chambers of the two rotors being spaced 90° apart, each chamber will be filled and discharged twice for each complete rotation of the rotors and balanced non-pulsating operation is assured with a constant rate of discharge from the pump and furthermore the hydraulic pressure on the rotors and the rotor shafts is balanced thus greatly reducing the load on the shaft bearings. Referring to Figure 2, it will be noted that there is sufficient clearance between the drive shaft 13 and the rotors so that the rotors may at all times revolve freely in their cylinder spaces without being subjected to any strain which might result from slight shaft bearing irregularity.

In order to effect sealing against escape of fluid from the pump housing past the end wall 12, I provide this wall with an annular groove 69 at its outer corner for a sealing ring 70 and which

may be of rubber. A comparatively thin hard steel friction washer 71 is applied against the outer side of the wall 12 and over the groove for engagement by the locking nut or ring 34. The pressure against the sealing ring will compress it for intimate engagement with the surrounding surfaces so as to effectively prevent leakage. The groove 69 is extended inwardly by a very narrow annular portion 72 around the fit diameter of the wall 12. This extended portion constitutes a spill groove and it is made larger in area than the compression of the rubber of the sealing ring 70 will require so that any of the rubber in excess of that required to effect sealing may move into the spill groove.

As best shown on Figure 3, ports 13 are provided in the middle plate 32 for connecting the outer ends of adjacent blade slots 62 so that any fluid leaking into the space at the backs of the blades can circulate back and forth between the two blades and act to accelerate the blades inwardly in cooperation with the blade accelerating springs 68. In order to prevent entrapping of oil behind the blades, which might interfere with their free and easy operation, release means are provided by connecting the valve slot spaces with either the discharge or the suction line. As shown on Figure 2, shallow channels 74 may be cut in the sides of the rings to connect the spaces behind the blades with the suction lines 51 and 56.

In order to prevent accumulation and entrapping of fluid in the space between the drive shaft and the pump operating parts, release channels 75 may be provided, these channels, as shown, being cut in the outer faces of the plates 31 and 33 for flow of surplus fluid from the space around the shaft to the suction line. Shallow channels 76 may also be cut in the inner face of the rings

so that any fluid which may be trapped between the blades and the rotors may flow into the discharge outlet.

It will be noted that in the pump shown and described, the rotors are alike, and likewise the rings and the separator plates are alike, so that these parts may be interchangeably used thus making for quick and easy assembly. These various parts may be inexpensively made as no costly precision work is required.

10 I have shown a practical and efficient embodiment of the various features of my invention but I do not desire to be limited to the exact construction, arrangement and operation shown and described as changes and modifications may be made without departing from the scope of the invention.

15 I claim as my invention:

20 A cylinder structure for fluid under pressure comprising a cylindrical wall having a removable end wall fitting into one end thereof to form a closure therefor, a clamping ring having threaded engagement with said cylindrical wall outside of said end wall for clamping said end wall in place, a thin metallic washer between said clamping ring and said end wall, the outer peripheral corner of said end wall being cut away to provide an annular groove entirely enclosed by said end wall, said cylindrical wall and said washer, sealing material in said groove compressed when said clamping ring is applied to said washer and forming a seal against the escape of fluid from within the cylinder structure, and a comparatively narrow annular groove in said end wall inwardly of said 25 sealing material groove and forming a continuation of said sealing material groove for receiving any overflow of the sealing material when said sealing material is compressed.

30 35 SHERWOOD C. BLISS.
